UNITED STATES PATENT OFFICE.

EMIL MALINOSKI, OF NANTICOKE, PENNSYLVANIA.

DESIGN FOR A SOCKET FOR TOOL-HANDLES.

SPECIFICATION forming part of Design No. 30,891, dated May 30, 1899.

Application filed May 8, 1899. Serial No. 716,887. Term of patent 14 years.

To all whom it may concern:

Be it known that I, EMIL MALINOSKI, a citizen of the United States, residing at Nanticoke, in the county of Luzerne and State of Pennsylvania, have invented and produced a new and original Design for Sockets for Tool-Handles; and I do hereby declare the following to be a full, clear, and exact description of the invention, such as will enable others skilled in the art to which it appertains to make and use the same.

In the drawings, Figure 1 is a plan view of the socket. Fig. 2 is a longitudinal section taken on the line $z z$ in Fig. 1. Fig. 3 is a cross-section taken on the line $y y$ in Fig. 2.

As shown in the drawings, the leading or material feature of the design consists of a socket for a tool-handle provided with a transverse opening at its upper part and a longitudinal chamber at its lower part, which is forked at its upper end, the forked portions of the said chamber being separated by a wedge-shaped partition.

A is the socket, and B is the transverse opening at its upper part, in which is placed 25 the head of a pickax or other tool.

C is the chamber arranged longitudinally in the lower part of the socket for the reception of the handle. The upper part of the chamber C is forked, forming two diverging 30 portions c, which are separated by a wedge-shaped partition d, the point of which faces the entrance to the chamber.

D are the holes for the fastening bolts or rivets. 35

I claim—

The design for a socket for a tool-handle, substantially as herein shown and described.

In testimony whereof I affix my signature in presence of two witnesses.

EMIL MALINOSKI.
